Patented Sept. 10, 1974

232,760

TOOL HOLDER FOR A LATHE TOOL, OR SIMILAR ARTICLE

Pasquale Joseph Lanese, Mayfield Heights, Ohio, assignor
to The Warner & Swasey Company, Cleveland, Ohio

Filed Sept. 11, 1972, Ser. No. 287,632

Term of patent 14 years

Int. Cl. D15—09

U.S. Cl. D54—6

FIG.1

FIG.2

FIG. 3

FIG. 4

FIG. 5

FIG. 1 is a pictorial view looking at the front and left-hand side of a tool holder for a lathe tool, or similar article embodying my new design;

FIG. 2 is a plan view looking at the bottom of the tool holder shown in FIG. 1;

FIG. 3 is a side elevational view looking at the right-hand side of the tool holder as it is shown in FIG. 1;

FIG. 4 is a rear elevational view of the tool holder of FIG. 1; and

FIG. 5 is a fragmentary perspective view at an enlarged scale showing a detail of the tool holder slot in the front of the tool holder of FIG. 1.

I claim:

The ornamental design for a tool holder for a lathe tool, or similar article, as shown.
